UNITED STATES PATENT OFFICE

JACK SCHWEIZER, OF RYE, NEW YORK

DESIGN FOR A TEXTILE FABRIC OR THE LIKE

Application filed November 11, 1932. Serial No. 45,877. Term of patent 8½ years.

To all whom it may concern:

Be it known that I, JACK SCHWEIZER, a citizen of Switzerland, residing at Rye, county of Westchester, and State of New York, have invented a new, original, and ornamental Design for a Textile Fabric or the like, of which the following is a specification, reference being had to the accompanying drawing, forming part thereof.

The figure is a surface view of a piece of textile fabric or the like, showing the design. One complete unit of the design is included within the dot and dash lines. The figure is

a view of one-half of the complete width of the design, the other indicated by the dotted lines at the upper end of the figure representing the other half of the width which is an exact duplicate of the half shown, the portion of the design at the upper end being next adjacent to the similar portion of the illustrated half of the design.

I claim:

The ornamental design for a textile fabric or the like, as shown and described.

JACK SCHWEIZER.
